US0D1077198S

(12) **United States Design Patent** (10) **Patent No.:** **US D1,077,198 S**
(45) **Date of Patent:** **** May 27, 2025**

(54) **HVAC SUPPORT**

(71) Applicant: **Eberl Iron Works, Inc.**, Buffalo, NY (US)

(72) Inventors: **John Eberl**, Williamsville, NY (US); **Justin Carr**, West Seneca, NY (US); **Jared Carris**, Orchard Park, NY (US); **Michael Weslowski**, West Seneca, NY (US); **Thomas Drahushuk**, Blasdell, NY (US); **Darryl Najewski**, Lancaster, NY (US); **David Rodriguez**, Buffalo, NY (US)

(73) Assignee: **EBERL IRON WORKS, INC.**, Buffalo, NY (US)

(**) Term: **15 Years**

(21) Appl. No.: **29/934,598**

(22) Filed: **Mar. 26, 2024**

(51) LOC (15) Cl. **23-04**

(52) U.S. Cl.

USPC **D23/354**

(58) **Field of Classification Search**

USPC D23/314, 354, 351, 386, 499; D6/512, D6/513, 567; D8/380

CPC .. F16M 1/00; F16M 3/00; F24F 13/32; A47B 43/003

(57) **CLAIM**

The ornamental design for an HVAC support as shown and described.

DESCRIPTION

FIG. 1 is a front, top, right perspective view of an HVAC support showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Broken lines illustrate portions of the HVAC support that form no part of the claimed design.

1 Claim, 5 Drawing Sheets
